UNITED STATES PATENT OFFICE.

HARRY A. PRELL, OF HARTFORD, WISCONSIN.

RADIATOR.

1,330,342.

Specification of Letters Patent. Patented Feb. 10, 1920.

Application filed March 24, 1919. Serial No. 284,596.

To all whom it may concern:

Be it known that I, HARRY A. PRELL, a citizen of the United States, residing at Hartford, in the county of Washington and 5 State of Wisconsin, have invented certain new and useful Improvements in Radiators, of which the following is a specification.

This invention is a radiator for automobiles, and more especially one of that type 10 having vertical water tubes; and the object of the same is to prevent freezing as far as possible.

Another object is to provide means whereby by a greater number of tubes may be opened 15 to the flow of water as the heat of the radiator increases.

Another object is to employ a thermally controlled valve for changing the course of the water.

20 Other objects will appear in the following specification and claims, and attention is drawn to the drawings wherein—

Figure 1 is a central vertical section through this improved radiator.

25 Fig. 2 is a transverse vertical section at right angles to the sectional line of Fig. 1.

Fig. 3 is an enlarged sectional detail of the filling tube and

30 Fig. 4 is a sectional detail on the line 4—4 of Fig. 3.

No novelty is claimed for the shell S of 35 this radiator, its filling nipple N and cap C, nor its inlet and outlet I and O. The inlet as usual leads from the top of the engine, the outlet leads preferably through a suitable pump into the engine jacket, and water is supplied from time to time through the nipple N as well understood.

Coming now to the details of the present 40 invention, partitions 1 and 2 extend across the interior of the shell at about the points shown, the front and shorter water tubes 3 connect and open through these partitions preferably near the front side of the radiator where they are subjected to considerable breeze; and other tubes 4, 5, 6 and 7 growing respectively longer toward the rear as shown, open also through the lower partition and extend up and completely through 45 the upper partition as shown. The lower ends of all tubes are by preference restricted as shown at 8 so as to retard the passage of water through them. The upper ends of the tubes 4, 5, 6 and 7 open through a grade plate 9, which is inclined from the rear wall 50 of the shell S downward toward its front

wall, and contacts with the upper partition 1 just in rear of the open ends of the front tubes 3. Above this wall are disposed baffle plates 10 which are in substantial alinement with it and by preference have fins 11 on their lower faces to prevent splashing and a wide space 12 exists between the inner edges of the baffles as seen in Fig. 1. Over the end of the inlet I also there is another 60 baffle 13. The plates 10 may incline forward as seen in Fig. 2 and may incline from the ends of the radiator inward toward its center or toward the space 12 as seen in Fig. 1. Above these plates is a 70 chamber 14 yet to be referred to. Beneath the lower partition 2 is another chamber 15 communicating with the outlet through a valve 16 capable of being set by hand. A pet cock 17 also opens from a high point 75 in the chamber 15, for a purpose to appear. Finally a large tube or conduit 18 connects and opens through both partitions, directly beneath and in alinement with the nipple N and there is an opening through the 80 grade plate 9 directly above this conduit, while of course the space between the baffle plates 10 is above this opening.

In Fig. 3 is seen a filling tube. This has a cylindrical body 20 preferably flanged at 85 21 at its upper end so that it may be dropped into the nipple N, and its exterior circumference is sufficient to permit it to be passed into the bore of the conduit 18 at its upper end as seen in Fig. 1. The body 20 is provided with upper and lower series of openings 22 and 23, the former adapted when the tube is in place to stand just beneath the nipple and the openings 23 adapted at this time to stand just above the partition 1 and within the space 12 between the two baffle plates 10. A damper or valve of the butterfly type 24, is pivoted within this tube near its lower end, and a rod 25 leads upward therefrom and connects with a thermal element 26 located within the tube near its upper end, the connections being such that when this element expands the valve is closed, and the reverse.

The action of this improved radiator will 105 be as follows: Having been coupled up, its valve 16 is closed and water is poured into the radiator to fill the chamber 15 completely full and to stand well within the lower ends of the tubes and the conduits and then the pet cock 17 is opened and the water 110 is drawn off to the line A. There should

now be as much water within the chamber 15 as could be accommodated above the present water level, throughout all the tubes to the overflow indicated at 30. Now when the 5 pet cock is closed and the valve 16 opened, the water flows into the jackets of the engine, through the pump referred to above. As it is drawn around through the pump and driven through the jackets, it flows in at 10 the inlet pipe 1 under the baffle 13, above the partition 1 and beneath the grade plate 9. Flowing into the openings 23, it passes down through the lower end of the filling tube 18, and again passes through the chamber 15 and onward. Very soon this water becomes warm, and its effect upon the thermal element 26 is to close partly and eventually to close fully the valve or damper 24. Now the water flowing in at the inlet must rise within the tube 18 and will 15 flow out the upper openings 22, when it runs over the plates 10 through this space 12 and down the restricted front pipes 3 into the chamber 15 and again throughout its course. 20 With the engine running the capacity of the restricted pipes 3 is not supposed to convey the full volume of water, so that it rises above the partition 1 and flows first through the pipes 4, then through the pipes 5 and 25 so on. Thus more and more pipes are brought into play as the water becomes hotter and the circulation more rapid, and of course the more pipes there are brought into use the larger the radiating surface and the 30 greater its effect upon the water flowing therethrough. When the engine comes to rest and the thermal element 26 again becomes cool, the damper 24 will open automatically and the water above the partition 35 40 1, if there be any, flows rapidly down the conduit 18 into the chamber 15, because the capacity of the conduit 18 is ample and the flow of water therethrough is not restricted.

A striking feature of this invention lies 45 in the fact that when the radiator is working with warm or hot water more and more of the tubes or pipes are in use; but when the water becomes cool and finally cold, the damper 24 opens and all the water collects 50 within the chamber 15, so that the pipes and tubes are drained. It is far safer to permit water to stand and to cool off within a chamber in bulk, than it would be to allow it to stand within radiator pipes exposed to cold 55 weather and purposely made extremely sensitive thereto, and therefore my invention providing automatic means for draining the pipes has its advantage when the car is idle. In summer time the entire filling tube 60 can be lifted out of place, as its use during that season is not essential.

The foregoing description and the drawings have reference to what may be considered the preferred or approved form of 65 my invention. It is to be understood that

I may make such changes in construction and arrangement and combination of parts, materials, dimensions, et cetera, as may prove expedient and fall within the scope of the appended claims.

70

Having thus fully described my invention, what I claim as new and desire to secure by Letters Patent is:—

1. In a radiator of the type described, the combination with a shell, spaced partitions 75 across the same, forward passages connecting and opening through the partitions and affording restricted communication between the chambers above and below said partitions, and an inlet into the upper and an outlet out of the lower chamber; of a series of other passages opening through the lower partition and extending through the upper partition, their upper ends rising to various heights, a relatively large conduit opening 80 through both partitions, and means for automatically retarding the flow of water through said conduit when the water becomes heated.

2. In a radiator of the type described, the combination with a shell, spaced partitions 90 across the same, certain tubes connecting and opening through the partitions and affording restricted communication between the chambers above and below said partitions, and an inlet into the upper and an 95 outlet out of the lower chamber; of a series of other tubes opening through the lower partition and extending through the upper partition, their upper ends rising to various heights, a relatively large conduit opening 100 through both partitions, a damper within said conduit, and a thermal element connected with said damper and adapted to close the same as the water increases in heat.

3. In a radiator of the type described, the 105 combination with a shell, spaced partitions across the same, forward tubes connecting and opening through the partitions and affording restricted communication between the chambers above and below said partitions, and an inlet into the upper chamber and an outlet out of the lower chamber; of a series of other tubes opening through the lower partition and extending through the upper partition, their upper ends rising to 110 various heights, a relatively large conduit opening through both partitions, a damper within the conduit, a filling tube in the upper end of the conduit and having a series of openings above the upper partition and a 115 second series of openings at its upper end, a grade plate connecting the upper ends of said tubes of various lengths and inclining toward said short tubes, and a thermal element within said filling tube connected 120 with the damper and adapted to close the latter as the water increases in heat.

4. In a radiator for motor vehicles, the combination with a shell having inlet and outlet openings at its upper and lower ends, 130

a partition across the shell beneath the inlet, a partition across the shell above the outlet, and a large conduit opening through said partitions; of a series of relatively small 5 pipes connecting and opening through the partitions, the front pipes being shortest and the others increasing in length toward the rear of the shell, a grade plate connecting their upper ends, baffle plates above the 10 grade plates and spaced from each other, a filling tube removably inserted in said conduit through the space between said baffles and having openings between the grade plate and the upper partition, and a thermally controlled valve within the filling tube beneath its openings, for the purpose set forth.

5. In a radiator for motor vehicles, the combination with a shell having inlet and 20 outlet openings at its upper and lower ends, a partition across the shell beneath the inlet, a partition across the shell above the outlet, and a large conduit opening through said partitions; of a series of relatively small

pipes connecting and opening through the 25 partitions, the front pipes being shortest and the others increasing in length toward the rear of the shell, a grade plate connecting their upper ends, baffle plates above the 30 grade plates and spaced from each other, a filling tube removably inserted in said conduit through the space between said baffles and having openings between the grade plate and the upper partition and another series of 35 openings at its upper end above the baffle plates, a valve within said tube beneath the lower opening, a thermal element within the tube beneath the upper opening, and a rod connecting the element and valve and adapted to close the latter when the water increases in heat.

In testimony whereof I affix my signature in presence of two witnesses.
